CURTAIN ROD THREADING DEVICE

Henry F. Baacke, Cowesett, R. I.

Application August 24, 1938, Serial No. 226,475

5 Claims. (Cl. 223—105)

My invention relates to a curtain rod threading device for hollow curtain rods to insure that the curtain rod may be threaded into the rod receiving channel or hem of the curtain without catching at any portion thereof. I am aware that others have provided curtain rod threading devices made of wire having arrow or spiral shaped threading outer ends of greater height than the height of the hollow curtain rod so as to 5 insure that the curtain rod will not catch in the curtain at the upper and lower surfaces thereof. So far as I am aware, no one has hitherto provided a curtain rod threading device having a flat threading outer end of greater height than said 10 10 insure that the curtain rod will not catch in the curtain at the upper and lower surfaces thereof. So far as I am aware, no one has hitherto provided a curtain rod threading device having a flat threading outer end of greater height than said 15 hollow curtain rod adapted to pierce a curtain rod channel and prevent the top and bottom edges from catching on the top and bottom walls of said curtain rod as the rod is being inserted therein, which flat threading outer end first has 20 its inner end offset laterally in one direction, then extends forward obliquely laterally from inner to outer end to have its outer end offset laterally in the opposite direction to provide lateral extensions offset in opposite directions from the 25 inner and outer ends of said threading outer end to prevent the sides of said curtain channel from catching on the side walls of said curtain rod as said rod is being inserted.

A further object of my invention is to provide 30 such a construction made of a single piece of bent wire constructed so as to spread the channel so that it positively cannot catch on the curtain rod as the rod is being inserted and which permits therefore the curtain rod to be guided therein into the most delicate fabric without injury thereto.

Further objects of my invention are to provide 35 a device simple to manufacture which may be quickly attached and detached from the curtain rod and also one which is relatively cheap and durable.

These and such other objects of my invention as may hereinafter appear will be best understood 40 from the accompanying drawing which illustrates 45 embodiments thereof.

In the drawing, Fig. 1 is a plan view of an embodiment of my invention attached to the end of a curtain rod and illustrating it in the act of being inserted in the hem of a curtain.

Fig. 2 is a sectional view taken along the line 50 2—2 of Fig. 1.

Fig. 3 is a vertical longitudinal sectional view 55 through a standard type of curtain rod showing this embodiment of my device in operative position in the end thereof.

Fig. 4 is a side elevation of the embodiment of my invention shown in Figs. 1 to 3.

Fig. 5 is an edge view of the embodiment of my invention shown in Figs. 1 to 4.

Fig. 6 is a side elevation of an alternative form 5 of my invention employing an alternative type of outer threading end.

Fig. 7 is an edge view of the embodiment of my invention shown in Fig. 6.

In the drawing, wherein like characters of reference generally indicate like parts throughout, 10 generally indicates a curtain rod threading device constructed in accordance with my invention.

Great difficulty has been experienced in threading the ends of curtain rods through the curtain rod receiving channels or hems of curtains without damage to the fabric. My invention aims to provide a device which will overcome these difficulties and so spread the curtain rod receiving 15 channel or hem 12 so that not only will the top and bottom of the curtain rod 14 be not caught within the top and bottom of said channel but also to laterally spread the channel to prevent the edges on the sides of the curtain rod from also 20 being caught in the side walls of said channel 12. To this end my invention comprises a curtain rod threading device for hollow curtain rods, comprising a flat threaded outer end 16 of greater 25 height than said hollow curtain rod 14 adapted 30 to pierce a curtain rod channel and prevent the top and bottom edges of said channel from catching on the top and bottom edges of said curtain rod as the rod is being inserted therein as shown 35 in Figs. 1 and 2, terminating in an inner end 18 of less height, said device also having an inner end 20 to be received by said hollow rod 14, said 40 flat threading outer end first having its inner end offset laterally in one direction as at 26, then extending forward obliquely laterally from 45 inner to outer end as at 22 to have its outer end offset laterally in the opposite direction as at 24 to provide the extensions 24 and 26 offset laterally in opposite directions of said outer threading end of the thickness of the curtain rod to prevent 50 the sides of said curtain rod channel 12 from catching on said curtain rod 14 as said rod is being inserted. While any type of a hollow curtain rod may be employed, I have shown in the drawing, a standard type of curtain rod having a flat 55 side wall 30 and ends 32 bent inwardly from the opposite top and bottom ends thereof to form an opposite side wall having an open center portion into which the inner end 20 of my device may be readily threaded.

- It is obvious, however, that while I have shown my invention in association with a flat curtain rod it may be employed for round or other shaped curtain rods with equal facility, and it is obvious that while I have described my invention in regard to height, etc., in the specification and claims as applied to a flat curtain rod it is immaterial in what position my improved device be inserted within the end of the hollow curtain rod.
- 10 In the preferred embodiment of my invention shown, I have provided a one piece curtain rod threading device comprising a single piece of wire having a threading loop 16 at the outer end thereof of greater height than said hollow curtain rod adapted to pierce the curtain rod channel 12 and prevent the top and bottom edges from catching on the top and bottom edges of said curtain rod as the rod is being inserted therein, terminating in inner ends 18 of less height and spaced free ends 20 extending rearwardly from said loop inner ends 18 to form an expanding tongue to be received by said hollow curtain rod, the threading loop 16 first having its inner end offset laterally in one direction, then extending forwardly obliquely laterally from inner to outer end to have its outer end offset laterally in the opposite direction to provide extensions offset laterally in opposite directions on said outer threading end to prevent the sides of said curtain rod holding channel in said curtain 15 from catching on said curtain rod as said rod is being inserted.
- 15 2. A one piece curtain rod threading device for hollow curtain rods comprising a single piece of wire having a hollow arrow headed threading loop at the outer end of greater height than said hollow curtain rod, said loop having its closed outer end pointed to pierce a curtain rod holding channel in said curtain, and diverging rearwardly to points where its height exceeds the height 20 of the hollow curtain rod to prevent the top and bottom of said curtain channel from catching on the top and bottom edges of said curtain rod as the rod is being inserted therein, from which points it is bent inwardly to form stop shoulders 25 on the top and bottom edges thereof to terminate in inner ends of less height, and spaced free ends extending rearwardly from said loop inner ends to form an expanding tongue to be received by said hollow curtain rod, said hollow arrow 30 headed threading loop first having its inner end offset laterally in one direction, then extending forwardly obliquely laterally from inner to outer end to have its outer end offset laterally in the opposite direction to provide extensions offset 35 laterally in opposite directions on said outer threading end to prevent the sides of said curtain rod channel from catching on said curtain rod as said rod is being inserted.
- 20 3. A one piece curtain rod threading device for hollow curtain rods comprising a single piece of wire having a circular threading loop at the outer end of greater height than said hollow curtain rod, adapted to pierce a curtain rod holding channel in said curtain and to prevent the top 40 and bottom edges of said curtain channel from catching on the top and bottom edges of said curtain rod as the rod is being inserted therein, and terminating in inner ends of lesser height, and spaced free ends extending rearwardly from 45 said loop inner ends to form an expanding tongue to be received by said hollow curtain rod, said circular threading loop first having its inner end offset laterally in one direction, then extending forwardly obliquely laterally from inner to outer 50 end to have its outer end offset laterally in the opposite direction to provide extensions offset laterally in opposite directions on said outer threading end to prevent the sides of said curtain rod channel from catching on said curtain 55 rod as said rod is being inserted.
- 25 4. A curtain rod threading device for hollow curtain rods comprising a threading outer end of greater height than said hollow curtain rod, adapted to pierce a curtain rod holding channel 60 in said curtain and prevent the top and bottom edges from catching on the top and bottom edges of said curtain rod as the rod is being inserted therein, terminating in an inner end of less height, and an inner end to be received by 65
- 30 70 75
- What I claim is:
1. A one piece curtain rod threading device for hollow curtain rods, comprising a single piece of wire having a threading loop at the outer end of greater height than said hollow curtain rod, adapted to pierce a curtain rod holding channel

in said curtain and prevent the top and bottom edges of said curtain channel from catching on the top and bottom edges of said curtain rod as the rod is being inserted therein, terminating in inner ends of less height, and spaced free ends 5 extending rearwardly from said loop inner ends to form an expanding tongue to be received by said hollow curtain rod, said threading loop first having its inner end offset laterally in one direction, then extending forwardly obliquely laterally from 10 inner to outer end to have its outer end offset laterally in the opposite direction to provide extensions offset laterally in opposite directions on said outer threading end to prevent the sides of said curtain rod holding channel in said curtain 15 from catching on said curtain rod as said rod is being inserted.

2. A one piece curtain rod threading device for hollow curtain rods comprising a single piece of wire having a hollow arrow headed threading 20 loop at the outer end of greater height than said hollow curtain rod, said loop having its closed outer end pointed to pierce a curtain rod holding channel in said curtain, and diverging rearwardly to points where its height exceeds the height 25 of the hollow curtain rod to prevent the top and bottom of said curtain channel from catching on the top and bottom edges of said curtain rod as the rod is being inserted therein, from which points it is bent inwardly to form stop shoulders 30 on the top and bottom edges thereof to terminate in inner ends of less height, and spaced free ends extending rearwardly from said loop inner ends to form an expanding tongue to be received by said hollow curtain rod, said hollow arrow 35 headed threading loop first having its inner end offset laterally in one direction, then extending forwardly obliquely laterally from inner to outer end to have its outer end offset laterally in the opposite direction to provide extensions offset 40 laterally in opposite directions on said outer threading end to prevent the sides of said curtain rod channel from catching on said curtain rod as said rod is being inserted.

3. A one piece curtain rod threading device for hollow curtain rods comprising a single piece of wire having a circular threading loop at the outer end of greater height than said hollow curtain rod, adapted to pierce a curtain rod holding channel in said curtain and to prevent the top 45 and bottom edges of said curtain channel from catching on the top and bottom edges of said curtain rod as the rod is being inserted therein, and terminating in inner ends of lesser height, and spaced free ends extending rearwardly from 50 said loop inner ends to form an expanding tongue to be received by said hollow curtain rod, said circular threading loop first having its inner end offset laterally in one direction, then extending forwardly obliquely laterally from inner to outer 55 end to have its outer end offset laterally in the opposite direction to provide extensions offset laterally in opposite directions on said outer threading end to prevent the sides of said curtain rod channel from catching on said curtain 60 rod as said rod is being inserted.

4. A curtain rod threading device for hollow curtain rods comprising a threading outer end of greater height than said hollow curtain rod, adapted to pierce a curtain rod holding channel 70 in said curtain and prevent the top and bottom edges from catching on the top and bottom edges of said curtain rod as the rod is being inserted therein, terminating in an inner end of less height, and an inner end to be received by 75

5 said hollow curtain rod, said threading outer end first having its inner end offset laterally in one direction, then extending forwardly obliquely laterally from inner to outer end to have its outer end offset laterally in the opposite direction to provide extensions offset laterally in opposite directions on said outer threading end to prevent the sides of said curtain rod holding channel in said curtain from catching on said curtain rod 10 as said rod is being inserted.

10 5. A curtain rod threading device for hollow curtain rods comprising an arrow headed threading outer end of greater height than said hollow curtain rod, adapted to pierce a curtain rod 15 holding channel in said curtain and prevent the top and bottom edges of said curtain channel

from catching on the top and bottom edges of said curtain rod as the rod is being inserted therein, terminating in an inner end of less height, and an inner end to be received by said hollow curtain rod, said arrow headed threading outer end first having its inner end offset laterally in one direction, then extending forwardly obliquely laterally from inner to outer end to have its outer end offset laterally in the opposite direction to provide extensions offset laterally in opposite directions on said outer threading end to prevent the sides of said curtain rod channel from catching on said curtain rod as said rod is being inserted. 10
